PREFABRICATED BATHROOMS AND PRE-
FABRICATED RESTROOMS
Albert L. Wokas, 22245 Thorofare Road,
Grosse Ile, Mich.
Filed Sept. 26, 1962, Ser. No. 226,214
6 Claims. (Cl. 4—2)

This invention relates to the prefabrication of rooms, especially restrooms which may or may not contain baths. It is especially concerned with the prefabrication of two restrooms which are built together as a single unit package ready for installation in a building. These package units are made up of walls, floors, ceilings, doors, and completely equipped interiors, including all the plumbing fixtures, water lines, and waste lines in place, tested and ready for use when the package units are delivered to the sites.

The invention is shown in the accompanying drawings in which:

FIGURE 1 is a top elevation in perspective of a simple twin restroom unit embodying the invention;

FIG. 2 is a perspective view of the unit of FIG. 1, showing how it may be lifted into place;

FIG. 3 is a view similar to FIG. 1 of a restroom unit in which the restrooms have bathtubs;

FIG. 4 is a view similar to FIG. 2 of the unit of FIG. 3;

FIG. 5 is a vertical cross section through the unit of FIG. 1;

FIG. 6 is a horizontal cross section through the unit of FIG. 1;

FIG. 7 is an enlarged, perspective view of the floor and center wall;

FIG. 8 is a vertical cross section of the floor and center wall with toilets mounted;

FIG. 8A is a reduced view, similar to FIG. 8 but with a different floor and toilets not mounted; and

FIG. 9 is a perspective view showing the plumbing in the center wall.

A restroom according to the invention is, from outward appearances, a single cubical unit with four walls, a floor and a ceiling. Two doors 4 (one designated for "Men" and the other for "Ladies"), are located such that they each permit entrance into one-half of the cubical unit. The unit is divided into two separate areas by the center partition 3 (see FIGS. 1 to 9). In each room of the two restrooms will be found completely installed and ready for use: finished walls, ceiling, floor, a wall-hung water closet 6, lavatory 7, mirror, light fixture, exhaust fan 9, heat ducts 10, and toilet accessories. The units may contain one of each plumbing fixture or a combination of two or more of each fixture, depending on the need. The size of the package restrooms is variable and is dependent on the building requirements. The units may also be modified in design so that the entire unit may be used for a "Men's" restroom or a "Women's" restroom, thus doubling the capacity for each unit. The same principles of the center system (see FIGS. 1 to 9) will be used on these modified units. The restrooms of this invention are intended for use in new construction but can also be installed in remodel work where space permits. They can be installed in all types of buildings, such as gasoline service stations, restaurants, factories, shops, retail stores, etc., and in every building that is erected where toilet facilities are needed. The exterior covering 11 of the restrooms will be such that it is weather-resistant and weathertight since it normally must be exposed until the building into which it is placed is itself completed.

The restrooms of this invention can have a permanent exterior 11 installed including a permanent roof, if the

2

package is to be used as an appendage onto a building or if it were to be used as a self-standing structure being used for restroom facilities only.

FIGS. 3 and 4 show that restrooms according to the invention which contain bathtubs are, from outward appearances, a single cubical unit which has four walls, a floor and a ceiling. Two doors 4 (which are an integral part of the package) are located such that they each permit entrance into one-half of the cubical unit. The cubical unit is divided into two separate rooms by the center partition 3. The pair of bathrooms, therefore, is, from outward appearances, a single cubical unit. However, it is divided by partition 3 into two separate bathrooms.

Each room of the pair will be completely finished from floor to ceiling and will contain: a wall hung water closet 6, lavatory 7, bath tub 8, vanity counter 5, mirror, lighting fixtures, exhaust fan 9, heat duct 10, and all bathroom accessories. The size of the units is variable but usually rectangular in shape. The plumbing fixtures are installed on the center partition 3 in a back to back pattern and shower stalls can be substituted for bath tubs where desired.

The units are intended to be used in new construction but can also be installed in remodel work where space permits. They can be installed in all types of buildings, such as motels, hotels, apartments, and all types of housing that are designed for two or more bathrooms.

The center wall system (see FIGS. 5 to 9) is the heart of the dual restroom or bathroom unit. The center wall system is created by uniting the monolithic floor 2 with the common dividing wall partition 3 into a structure that resembles an inverted T in cross section. The floor 2 is designed structurally to fit the type of building into which the finished package is placed. If the unit is to be installed in a house that is built of wood framing, the floor 2a for the package will use wood framing for its structural strength (see FIG. 8A). If the unit package is installed in a building or house that has a concrete floor 2, the package unit will have a concrete or steel type floor (see FIGS. 5, 7, and 8). The package units are designed such that they lend themselves to a slab construction type of installation. This permits the completed units to be installed in those buildings where there is no basement or crawl space available. It fits in multi-story buildings without the need of exposing piping and plumbing on the ceiling below the unit.

The floor is, therefore, normally designed without any openings, thus eliminating the need to make any plumbing connections under the floor once the complete package unit is set into place. This unique feature of the center wall system has many advantages and the most outstanding advantage is that it permits the completed unit to be set in place prior to installing the field rough plumbing which is later connected to the finished unit at one end of the divider wall just above the finished floor line (see FIGS. 2, 4, 6, 7, and 9). Therefore, all final connections between the field rough plumbing and the finished package plumbing 12 are made at grade level. In those cases where clearances and wall space are at a premium, a "half-moon" cut out 13 (see FIG. 7) in the edge of the floor just below the end of the divider wall can be included. This permits making the rough plumbing connections at grade level and eliminates exposure of any piping.

In buildings such as motels, hotels, apartments, commercial buildings, service stations, etc., where concrete slab construction is normally used for floors, package units using some combination of steel decking, concrete and wood are recommended (see FIGS. 7 and 8). When this type of floor 2 is made part of the center wall system, it

provides stability and permanency equal to or exceeding the remaining part of the building. This floor 2, along with the divider wall partition 3, becomes the "back bone" of the package unit since all the exterior walls depend on the floor and divider wall partition for their support and stability. The floor of the system also is an integral part of the structure that permits the restrooms of the invention to be picked up, moved and set in place without damaging the unit (see FIGS. 2 and 4). Depending on the need, lifting rods 14 may be built into the framework of the restrooms (see FIGS. 2, 4, 5, and 6). These rods are securely anchored to the floor and a minimum of strain is put on the plumbing, fixtures and walls when the unit is picked up and set into place with a crane. The units may also be moved by using a crane and slings, fork lift trucks or positioned by the use of rollers or casters.

The second component and the key part of the center wall system is the divider wall partition 3 that makes up the vertical leg of the inverted T. This divider wall extends from one side of the floor to the other and divides the one piece floor into two areas, thus permitting the development of dual room unit. The divider wall 3 is made up of two rows of re-enforced vertical wood or steel studs. The two rows of studs are spaced properly apart so as to permit the installation of all mechanical equipment in this space. (The requirement is to make a box-like structure of known materials with adequate space and strength to serve the intent of the unit.) During shop fabrication the divider wall is secured to the floor with anchor bolts 15 or tack welds (see FIGS. 7, 8, and 8A) forming a rigid unit. The divider wall system permits the servicing of two rooms from a common wall unit that contains all the mechanical, electrical, and heating equipment necessary for the functioning of the two rooms.

The carriers 16 to which the back to back wall hung water closets are secured are an integral part of the divider wall structure and are built in as a part of the wall (see FIGS. 5, 6, 7, 8, and 9). A carrier must be used with a wall hung closet and carriers are usually manufactured units that are separately installed in the walls during construction of a building. The carriers 16 are part of and built into the stud wall divider partition 3. The carrier 16 partition 3 is then secured to the floor. The purpose for using this unique built-in carrier 16 is to permit the use of wall hung water closets which then eliminates the need of having the waste pipes go through the floor.

The carrier 16 and the divider wall 3 structure are so designed that when the two wall hung water closets 6 are set in place back to back and secured with nut 17 and through bolt 18, the squeezing action of the nut 17 and through bolt 18 prohibits any movement between the water closets 6 and connecting plumbing waste pipes 19, thus eliminating any possible water leakage at this critical point.

The plumbing waste lines 12 that connect to the wall hung water closets are placed in a horizontal position with a slight downward slope toward the edge or end of the divider wall and the floor. This unique method of installing wall hung water closets and horizontal waste pipes located above the floor line permits the discharge end of the waste pipes 12 to emerge out of the side of the package units, thus eliminating any need for under floor connections. If it is not desirable to have the waste pipe emerge out of the side of the unit, a 90° turn in the waste pipe just inside the edge of the floor through a pre-cut half-moon shaped hole 13 will provide the same end result. A vertical plumbing vent stack 20 is connected to the horizontal waste pipe 12 and extends through the top of the package units. (See FIGS. 2, 4, and 5.) The waste pipe 21 (FIG. 9) from the lavatories is connected to this vent stack 20 and this waste pipe 21 is also re-vented by line 22 to the stack 20. In the bath tub unit the waste line 23 from the bath tubs or shower stalls are connected to the horizontal waste pipe 12 and these waste lines are also re-vented by line 24 into the main vent stack.

5 The entire plumbing system including all waste lines for all plumbing fixtures, vent stacks, re-vent lines, hot 25 and cold 26 water lines, and wall hung water closet carriers are built into the divider wall 3. The hot and cold water lines are installed with ends that emerge out the end of this divider wall adjacent to the waste pipe outlet.

10 The electrical service 27 to the package enters at the end of the divider wall and circuits are extended to various points in the rooms. (See FIGS. 2 and 4.) A hot air heat duct 10 and registers are installed in the space in the center of the divider wall and are ready for use when connected to the main supply. Electric heat or hot water heat may be provided if desirable.

15 The rigid center wall and floor combination (inverted T) is the nucleus around which the dual rooms are built. To complete the building of the packages, standard construction practices and material are followed although they will all be tailored to fit into a process for mass production of the units. The walls of the package units can be built using standard wood or steel studding. The exterior of the packages will be covered with material such as cement board or hard board depending on its final exposure.

20 The interior of the package buildings can be of any material specified, such as ceramic tile, plaster board, laminated plastics, etc. The completed package will include all plumbing fixtures installed, tested and ready for use. All accessories, such as mirror, towel holders, vanity counters, etc., will be installed at the factory. Both doors 30 will be hung complete with hardware and in operating order.

25 A completed unit built in the factory can be shipped to the site, set in place and be ready for final hook-up. The final attachment would consist of one waste line connection, one hot and cold water connection, one electrical connection, one vent line connection and one heat duct connection. All connections are made on the exterior of the unit and the package restrooms or package bathrooms are ready for use.

30 The intent of this invention is to provide a completely integrated dual restroom unit that can be built in a shop or factory under mass production conditions, delivered to the site, and installed in a building that is under construction. This invention does not limit itself to any 45 special kind or type of building but is so designed to fit into any and all conceivable types, sizes, or shapes of buildings that require restroom or bathroom facilities. In essence, the dual room unit will be set in place and the building structure will be built around it. The center wall-floor system permits the flexibility to meet the requirements of code, transportation, durability, and appeal. It permits a simple method of "hook-up" into the building 50 designs and shapes. They will be completely built in the shop, delivered to the site by truck or rail, and set in place with the use of cranes or skids. Once the services are connected to the openings or outlets on the exterior of the units, the completely equipped restrooms are ready for instant use.

55 60 What is claimed is:

1. A portable prefabricated restroom structure to provide two restrooms and adapted for insertion in a building to form a part thereof comprising a unitary, self-sustaining, rigid floor having sufficient strength to support the structure as a unit situated apart from a building into which it will be installed, a central wall rigidly secured to and across the floor to divide the floor into two areas forming two floors for said two restrooms, said central wall being hollow, restroom fixtures mounted on said wall, 65 plumbing elements for the restroom fixtures including a waste pipe located inside said hollow central wall, all of said plumbing elements being mounted on and supported by said central wall, said floor being separate from and unconnected to said plumbing elements except through 70 said central wall and said waste pipe in its entirety being 75 said central wall and said waste pipe in its entirety being

located above said floor, said floor and central wall providing an inverted T-shaped portable load carrying framework for said two restrooms.

2. The structure of claim 1 including identical restroom fixtures on opposite sides of said central wall and installed back to back thereon and supported directly by the central wall.

3. The structure of claim 1 including plumbing connections on said plumbing elements for connection to the plumbing system of a building in which the restrooms are to be installed, all of said plumbing connections being located on a level above the floor.

4. The structure of claim 1 including ceiling and wall means for the two restrooms, an electrical system and a ventilating system for said restrooms, said systems and said plumbing elements having all their connections for attachment to the electrical, ventilating, and plumbing systems of a building located adjacent said ceiling and wall means and separated from said floor structure.

5. The structure of claim 1 including a pair of carrier brackets anchored in said floor and projecting above the

top of the central wall and providing means for lifting the structure.

6. The structure of claim 1 including back to back toilet carriers mounted on said central wall.
